UNITED STATES PATENT OFFICE

161,901

OVERSHOE

George F. Bushway, Andover, Mass., assignor to Tyer Rubber Company, Andover, Mass., a corporation of Massachusetts

Application January 6, 1950, Serial No. 7,042

Term of patent 14 years

(Cl. D7—4)

To all whom it may concern:

Be it known that I, George F. Bushway, a citizen of the United States, residing at Holt Road, Andover, county of Essex, Commonwealth of Massachusetts, have invented a new, original, and ornamental Design for an Overshoe, of which the following is a specification, reference being had to the accompanying drawing, forming a part thereof.

In the drawing, the single figure is a perspective view showing the front and side of an overshoe embodying my new design.

I claim:

The ornamental design for an overshoe, substantially as shown.

GERGE F. BUSHWAY.
